ANIMAL DISPLAY BENCH

Andrew Wilson Bow, Detroit, Mich.

Application May 22, 1939, Serial No. 274,933

5 Claims. (Cl. 119—15)

This invention relates to wall structures and is particularly concerned with wall structures that may be readily assembled or disassembled.

An object of the invention is to provide means for associating two walls in perpendicular arrangement so that accidental displacement of said walls is impossible.

In carrying out the above object it is a further object to provide one of said walls with a hook 10 that is adapted to be inserted within a cut-out portion of the other wall so that when the walls abut one another the hook prevents displacement thereof.

It is a further object to provide means for preventing the hook carrying wall from being moved away from its abutting engagement with the other wall.

A still further object of the invention is to provide a vertical wall having a plurality of 20 spaced separating walls associated therewith so that each of the separating walls has an edge thereof abutting a face of the vertical wall, means being provided for simultaneously locking said separating walls in position, whereby displacement thereof with respect to the vertical wall is prevented.

Further objects and advantages of the present invention will be apparent from the following description, reference being had to the accompanying drawing wherein a preferred embodiment of the present invention is clearly shown.

In the drawing:

Fig. 1 is a view, in perspective, of a preferred form of wall structure.

Fig. 2 is a fragmentary end view of the structure shown in Fig. 1.

Fig. 3 is a fragmentary view taken in the direction of the arrow 3 in Fig. 2.

Fig. 4 is a fragmentary view taken in the direction of the arrow 4 in Fig. 2 showing the arrangement of the hooks used in connection with the separating walls.

Fig. 5 is an enlarged fragmentary view, taken on the line 5—5 of Fig. 4, of one of the hooks in position with respect to the vertical wall.

Fig. 6 is a fragmentary view taken in the direction of the arrow 6 in Fig. 1.

Fig. 7 is a sectional view taken on line 7—7 of Fig. 1, and

Fig. 8 is a fragmentary view of the vertical wall showing the construction used to form adjacent cut-outs.

The present invention is particularly directed to wall structures which may be readily assembled or disassembled in a minimum of time and with a minimum of effort, and which are strong and remain in position against accidental displacement of the walls thereof. Such knock-down or portable structures, as they may be termed, are used as benching for the exhibition of dogs, or

other animals wherein the separating walls must necessarily be positively held in position against displacement thereof. Structures of this type may also be utilized as stalls, portable booths for exhibition purposes, display stands, or for many other related uses wherein ease of assembly and stability of construction are essential details.

Referring to the drawings, and particularly to Fig. 1, 20 indicates a vertical wall which may be formed from any well known constructional material, preferably plywood. The wall 20 has hinged thereto a floor or bottom wall 22, by means of hinges 26. The hinges 26 are preferably of the type known as piano hinges which facilitate assembly due to the rigidity of construction. Of course the usual type of strap or butt hinge may also be used if desired. When assembling the structure the floor 22 is opened to the position shown in Fig. 2, which is perpendicular to the wall 20. The entire assembly is placed on the 10 floor or ground, or upon horses as shown at 30. The vertical wall 20 is provided with a plurality of spaced cut-out portions 32 adjacent the top edge thereof, which may be made into double cut-outs as shown in Fig. 8, when desired, wherein a strap 34 is placed over the cut-out 32, and a screw 36 is passed therethrough and screwed into the wall. In this manner two apertures or cut-outs can be formed with a minimum of effort.

In order to form stalls, or compartments, and also to hold the wall 20 in its vertical position with respect to wall 22, a plurality of spaced vertical separating walls 38 are provided either on one side only of wall 20 or on both sides of wall 20 if another bottom wall 22 is provided on the opposite side of wall 20. The walls 38 are each equipped with an upwardly turned hook 40 at the upper corner thereof, which is adjacent the wall 20. In the assembly of the separating walls, the end of hook 40 is inserted through the aperture 32, and then the separating wall is rotated downwardly around the hook until the edges of the wall 38 abut a face of wall 20 and wall 22. In this position the wall 38 cannot be displaced laterally outwardly since the hook 40 engages the strap 34. To prevent longitudinal or sideward movement of the wall 38, each of the said walls is provided with one or two pins 42 which fit into apertures 44 in the floor 22. The apertures 44 are substantially aligned with the cut-outs 32 so that the separating walls 38, when in place, are substantially perpendicular to walls 20 and 22.

It is apparent that the walls 38 cannot be displaced with respect to the walls 20 or 22, except by upward movement of the walls 38 around the hooks 40. In order to eliminate accidental movement in this direction, I have provided each of the separating walls with a notch 46 therein adjacent the lower edge thereof. The floor 22 has hinged thereto a locking member 48 which has a 50 55 60 65 70 75 80 85 90 95 100 105 110 115 120 125 130 135 140 145 150 155 160 165 170 175 180 185 190 195 200 205 210 215 220 225 portion 50 adapted to interfit with the notches 46 when the member 48 is in the position shown in Fig. 1. Thus when all the separating walls 38 are in position, the member 48 can be brought into interlocking position therewith and simultaneously lock each one of the walls 38 in position wherein the walls cannot be disassembled with respect to walls 20 or 22 without first removing the member 48 to the position shown in dotted lines in Fig. 2. Heretofore it has been necessary to individually lock each wall in place in structures of this type, and it is manifest that the simultaneous locking action of member 48 materially reduces the time required to set up this assembly as well as making the entire structure more rigid.

In the drawing it will be noted that separating walls 38 may be placed on either side of the vertical wall 20. Thus, the hook from a wall 38 on one side of wall 20 lies substantially against the side face of a separating wall 38 placed on the opposite side of the wall 20, since the walls 38 are preferably substantially aligned. The disposition of the hooks is clearly illustrated in Figs. 3 and 4.

In order to improve the appearance at the ends of the structure, a special end wall 52 is provided. The wall 52 comprises two sections 54 and 56 that are hinged together if separating walls are used on both sides of wall 20. The inside faces of the sections 54 and 56 are each provided with a downwardly extending pin 58 that fits within apertures 42 in the floor 22. A strap 60 is utilized to hold the wall 52 in place, as shown in Fig. 6, and is passed through one of the cut-out portions 32 in the wall 20, and is then bolted to each of the sections 54 and 56. In this manner the end wall 52 is easily assembled and is rigidly held in place against displacement.

The walls may be provided in any desired length and with any desired spacing of separating walls. It is apparent that a structure as disclosed can be quickly and easily assembled or disassembled. When the walls are knocked-down and folded together all sections are substantially flat to facilitate packing and transportation. The hooks 48, 42 and 58 can all be countersunk and made from flat stock if desired, so as to increase the ease of packing.

While the embodiment of the present invention as herein disclosed, constitutes a preferred form, it is to be understood that other forms might be adopted, all coming within the scope of the claims which follow.

55. What is claimed is as follows:

1. An exhibit stall for animals comprising in combination, a floor section, a vertical wall running longitudinally of said floor and associated therewith, a plurality of spaced separating walls adapted to engage the vertical wall and abut the vertical wall and the floor perpendicularly, and means for associating the floor with the separating walls at a point remote from the vertical wall, said means being effective to simultaneously interlock with each of said separating walls adjacent the lower edges thereof only.

2. An exhibit stall for animals comprising in combination, a floor section, a vertical wall running longitudinally of said floor and associated therewith, a plurality of spaced separating walls adapted to engage the vertical wall and abut the vertical wall and the floor perpendicularly, and an interlocking portion hinged longitudinally of

the floor at the side opposite the vertical wall and adapted when raised to a position perpendicular with the floor and substantially parallel with the vertical wall to concomitantly lock with each of said separating walls adjacent the lower edges thereof only.

3. An exhibit stall for animals comprising in combination, a wall, a pair of walls hinged longitudinally to the first-mentioned wall adjacent one edge and on opposite sides thereof and adapted to provide a floor on both sides of said first-mentioned wall when placed perpendicular thereto, said first-mentioned wall having an aperture therein at a point spaced from the hinged edge thereof, two separating walls adapted to be placed perpendicular with respect to the first-mentioned wall and the second-mentioned walls, means to hold the separating walls in substantially perpendicular relation to the first-mentioned wall, said separating walls being in substantial alignment on either side of the first mentioned wall, a hook associated with the face of each separating wall and adapted to fit within said aperture and lie substantially adjacent to the face of the other separating wall for locking the separating wall to the first-mentioned wall and means secured to the second-mentioned walls and interlocking with a portion of the separating walls for preventing displacement of the separating walls when said separating walls are in position whereby said hooks can not be removed from said aperture, said means being shiftable for permitting disassembly of the walls.

4. An exhibit stall for animals comprising in combination, a floor, a vertical wall associated longitudinally with said floor adjacent the center thereof in substantially a T formation, an aperture adjacent the upper edge of said wall, separating walls adapted to abut the floor and first wall substantially perpendicularly and in alignment on opposite sides of the first wall, hooks secured to the separating walls and adapted to be inserted within said aperture, means on said separating walls adapted to cooperate with apertures in said floor for preventing lateral or longitudinal displacement of said separating walls with respect to the first wall and the floor and means secured to the floor for holding said separating walls from upward movement with respect to the floor whereby the hooks are prevented from displacement with respect to said apertures.

5. An exhibit stall for animals comprising in combination, a floor, a vertical wall positioned centrally longitudinally with respect to the floor, and having spaced apertures adjacent the upper edge thereof, a plurality of separating walls adapted to substantially abut the floor and the vertical wall in perpendicular relation thereto and arranged so that each wall of a pair thereof is on an opposite side of the vertical wall and in substantial alignment with the other wall of said pair, hooks associated with said separating walls and adapted to be inserted within said apertures, means cooperating with said separating walls and passing into apertures in the floor for assisting in holding said separating walls in one position with respect to the first wall and the floor and means for holding said separating walls from upward movement with respect to the floor, said means being effective to lock all of said separating walls in assembled relation.

ANDREW WILSON BOW.
